UNITED STATES PATENT OFFICE.

ALESSANDRO TARABORRELLI, OF PROVIDENCE, RHODE ISLAND.

CIGARETTE HOLDER.

Application filed September 27, 1919, Serial No. 326,701. Renewed January 14, 1924.

To all whom it may concern:

Be it known that I, ALESSANDRO TARABORRELLI, residing at Providence, in the county of Providence and State of Rhode Island, have invented new and useful Improvements in Cigarette Holders, of which the following is a specification.

This invention relates to cigarette holders, and the principal object of the invention is to provide clamping means for clamping the cigarette to hold the same in place. Another object of the invention is to make the device in the shape of a human being, using the arms as the clamping jaws and the legs the means for working the jaws.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a side view of the device;
Figure 2 is a plan view;
Figure 3 is a plan view with parts in section.

In these views 1 indicates a tube having a mouth-piece 2 formed at one end and its other end adapted to receive the cigarette. On top of this tube is located the figure 3 which is formed of two halves by dividing the figure longitudinally. A pin 6 is secured to the tube and each half of the figure

is provided with a perforated projecting part 5 for engaging said pin so that the two parts of the figure are pivotally supported upon the tube. A spring 8 is carried by the pin 6 and has its extremities engaging the legs 7 of the figure, this spring tending to press the upper parts of the two halves of the figure together with the arms 4 engaging the cigarette. When it is desired to remove the cigarette from the holder it is simply necessary to press inwardly upon the legs 7 to separate the arms of the figure to cause them to release the cigarette.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A holder of the class described comprising a tube, a pin projecting therefrom, a body divided longitudinally into two halves, with each half pivoted on the pin intermediate the ends, clamping members at the front ends of said halves, handle members at the rear ends of said halves (and spring means on the pin and engaging the lower parts of the halves) for forcing the clamping members into engagement with the article held by the tube.

In testimony whereof I affix my signature.

ALESSANDRO TARABORRELLI.
